REPRODUCTION OF SOUND

John Eggert, Leipzig-Gohlis, and Richard Schmidt, Dessau, Germany, assignors to I. G. Farbenindustrie Aktiengesellschaft, Frankfort-on-the-Main, Germany

No Drawing. Application March 16, 1934,
Serial No. 716,006. In Germany May 8,
1930

4 Claims. (Cl. 274—46)

Our present invention relates to a process for the reproduction of sound.

One of its objects is an improved process for the reproduction of sound. Further objects will 5 be seen from the detailed specification following hereafter.

According to this invention we have found that the undesired ground noise in the reproduction of photographic sound records is considerably 10 reduced by coating the film with a thin layer of a liquid which is uninflammable at the temperature prevailing in the gate of the reproducing apparatus and having a refracting index which is approximately the same as that of the support. 15 The effect of the invention will be appreciated when considering that this holds true already for the reproduction of sound records which are played for the first time and is increased with the number of performances inasmuch as it compensates also for the scratching of the sound 20 track caused by the use of the film. The application of the invention is particularly useful in the case of photographic sound records registered on lenticular film. With these films the lenticular elements cause considerable ground 25 noise, even in case of the lenticular elements being eliminated by one of the known processes because the planing processes do not work as accurately as it is desirable. The lenticular elements may be any of the known kind such as 30 rounded studs or picots, or cylinder lenses extending in longitudinal or transverse direction of the film.

The films may be wetted on one side only or on 35 both sides in the breadth of the sound record. It is, however, preferable to coat them on both sides with a thin layer of liquid. The coating of liquid may be applied by pad continuously wetted with the liquid, or it may be applied by a coating roller, or a suitable nozzle or in any other 40 suitable manner. The liquids are preferably easily volatile so that they can be removed by evaporation. Suitable liquids are, for instance, halogenated hydrocarbons such as carbon tetrachloride, or there may be used animal and vegetable 45 oils which have no tendency to form resinous products which would soil the apparatus. If the liquid is nonvolatile it may be removed by an easily volatile solvent which can be distilled off for recovering the coating liquid.

The wetting of the film may be effected prior 50 to its introduction in the projector or also while in the projector, for instance, while passing through the gate. The film, after leaving the

gate is preferably led to a device by which the wetting liquid is stripped off and the film is dried.

What we claim is:

1. In the process of reproducing sound from a photographic sound record the steps which comprise coating the film having an emulsion layer and a support and being scratched, at most, in a minor degree in the breadth of the sound record on at least one side with a liquid being uninflammable at the temperature prevailing in 10 the gate of the reproducing apparatus and having a refractive index approximately equal to that of the support prior to reproduction, reproducing the sound while the liquid is applied to the film, and removing the liquid from the 15 film after reproduction.

2. In the process of reproducing sound from a photographic sound record the steps which comprise coating the film having an emulsion layer and a support and being scratched, at most, in a minor degree in the breadth of the sound record on both sides with a liquid being uninflammable at the temperature prevailing in the gate of the reproducing apparatus and having a refractive index approximately equal to that of the support 20 prior to reproduction, reproducing the sound while the liquid is applied to the film, and removing the liquid from the film after reproduction.

3. In the process of reproducing sound from a photographic sound record recorded on lenticular film having an emulsion layer and a support and being scratched, at most, in a minor degree the steps which comprise coating the film in the 30 breadth of the sound record on both sides with a liquid being uninflammable at the temperature prevailing in the gate of the reproducing apparatus and having a refractive index approximately equal to that of the support prior to reproduction, reproducing the sound while the liquid 35 is applied to the film, and removing the liquid from the film after reproduction.

4. In the process of reproducing sound from a photographic sound record the steps which comprise coating the film which is scratched at most in a minor degree in the breadth of the sound record on at least one side with carbon tetrachloride prior to reproduction, reproducing the sound while the carbon tetrachloride is applied 45 to the film, and removing the carbon tetrachloride from the film after reproduction.
